UNITED STATES PATENT OFFICE.

RUDOLPH J. MEISER, OF CINCINNATI, OHIO.

APPARATUS FOR TANNING.

SPECIFICATION forming part of Letters Patent No. 366,785, dated July 19, 1887.

Application filed December 11, 1886. Serial No. 221,332. (No model.)

To all whom it may concern:

Be it known that I, RUDOLPH J. MEISER, a citizen of the United States of America, and a resident of Cincinnati, in the county of Hamilton and State of Ohio, have invented certain new and useful Improvements in Apparatus for Tanning, of which the following is a specification.

In the process of tanning leather as heretofore practiced the "sides" of leather have been suspended in the tannic acid or other tanning fluid or agent by being folded over laths or sticks at intervals in the vat about midway of the ends of the sides. In this way a raw streak has been left at such portion of the leather as lies upon the supporting lath or stick, and even when this portion is changed and moved away from its contact with such support the tanning process thereat is not so far advanced as the remainder of the leather. Another method more favored at present is that of suspending the sides at the head and tail ends thereof from hooks or pegs provided in each end of a frame rocking on a pivot, which moves and carries the suspended leather through the liquid in the vat, but always in unison, and the relation of all parts of one hide to those of another being constant, and on account of the unevenness and irregularity in the surface of the leather the tanning agent is not allowed to come in contact with all parts of such leather to such regular and uniform extent as to secure an even tanning thereof, and to secure in the tanning of leather the regular, uniform, and perfect effect thereon produced by the tanning agents is the object of the present invention; and it consists, in substance, in the combination, with a suitable actuating mechanism, of a pair of suitably-journalized bars, each of which is provided with a series of hooks or leather-supports above its center of vibration and a similar series below its center of vibration, all arranged in relation to a tanning-vat and for operation substantially as hereinafter described.

In the accompanying plate of drawings, the apparatus constituting the present invention is illustrated, in which—

Figure 1 is a plan view of a vat in which leather is tanned, and having located therein the parts constituting the present invention. Fig. 2 is a longitudinal vertical section on line

xx of Fig. 1. Fig. 3 is a transverse vertical section of the same on line *YY*. Fig. 4 is a view in detail, to be hereinafter referred to.

55

In the drawings, *A* represents a vat or tank for holding a tanning-liquid, in which the leather to be tanned is immersed, of which *B* *B* are the side walls, and *B' B'* the end walls. *C* and *D* are bars arranged one in each end of the vat, at the top thereof. These bars *CD* are each provided with two rows or series, *a a'*, (upper and lower,) of hooks *E*, or other projections for supporting leather, which extend from the inner side of said bars. The series *a* of hooks *E* is arranged to alternate with the hooks of the other row or series, *a'*, on each bar, as seen in Fig. 3. Each of the supporting bars *CD* is hung by a pivot or journal, *b*, in the side walls of the vat, and is susceptible 70 of a to-and-fro movement thereon when controlled and actuated by suitable mechanism—such, for instance, as will be now shown. The bar *C* has a rigid upward arm, *F*, which is pivoted to a connecting-rod, *G*, which at its 75 other end, *d*, is hung on the outer end of a crank, *H*, on a driving-shaft, *J*. The movement of the crank *H* imparts, through the connecting-rod *G*, to the arm *F* of the pivoted bar *C* a reciprocating motion, which oscillates the 80 bar *C* about its center or journal *B* backward and forward; or, in other words, while the upper side of the bar *C* is carried or moved inwardly, its under side below its journal is carried in the opposite direction, or outwardly, 85 and vice versa, under the action of the driving mechanism.

K is a connecting-rod which joins the arm *F* of the bar *D*, and through this connecting-rod *K* the bar *D* is oscillated simultaneously 90 with the bar *C*, and with its upper and lower hooks carried in the same relative directions therewith—that is, when the upper side of the bar *C* moves inwardly the upper side of the bar *D* moves outwardly, and the lower side of 95 one bar at such time moving outwardly while the other inwardly, and vice versa, in the continued operation.

It will be seen from the description of a mechanism substantially such as above described 100 that in supporting the leather, hides, or skins to be tanned upon the hooks *E*, the first side of leather being upon the upper hook, or in the series *a* of hooks *E*, and the next adjacent side

upon a lower hook, or one of the series a^2 , and so on, in the operation of such parts used for carrying out this invention, as described, all the portions of leather on the upper hooks 5 at one time are moved forward, while the portions on the lower hooks are moved backward, or in the opposite direction, and vice versa, all as is plain; and it is evident in the continued operation of the parts each side of 10 leather moves as to its relation to the next adjacent side, in a different direction, and the relative position of every part of each side in relation to that of each and every other side is always changing and is never for an instant 15 the same.

The connecting-rod G between the crank H and the rigid arm F of the pivoted bar C is provided with a vertical slot, g, which lies over the pin h of the rigid arm F, and the 20 connecting-rod is thus adapted to be detached from the driving mechanism when desired. It will be seen from an inspection of the drawings, Figs. 2 and 4, that the turned-up portions m of each hook E of the series a a^2 of hooks is in line with the center of rotation of their 25 respective bars. The hides or sides X, being first punctured or pierced and hung on the hooks E, are in this way conveniently suspended, and when it is desired to remove the leather 30 from its suspension the bar C, through the leverage of its rigid arm F, or otherwise, (the connecting-rod G being first detached,) is swung with its inner or hook side downwardly on its center a sufficient distance and in a 35 manner to bring the turned-up portion m of each hook E in a downwardly-inclined position, as seen in Fig. 4, and, as is obvious, the sides from their weight and tension will slip off the hooks. This method of releasing one 40 end of each side is very practical and of great convenience in the carrying out of this invention. As the leather suspended between the hooks of the two bars C D is more or less taut, and the exertion of considerable strength 45 would ordinarily be required in the displacement of the one end of each side from its respective hook in the practice of the method above described, the removal of the one end of each hide or side, as will be seen, is automatic 50 and most simple. One end of each hide having been displaced from its respective hook, the other end is then removed from its other hook by lifting the hide in a manner to draw it off such hook.

55 While in the description and illustration of the method of changing or varying the position of every part of each side in relation to the position of every part of each and every alternate side it has been stated and shown 60 that every side is moved to and fro, but always in a reverse direction to that of the next adjacent side, the same result would be in a degree accomplished by suspending every other side immovably and vibrating the alternate or intermediate sides; but this would not be so effective in the result obtained as where

every side is vibrated and in a direction the reverse of that of the next adjacent side.

It is obvious that from the agitation of the sides of leather in relation to the other sides 70 in the tanning-liquid in a vat, as described, a most full and complete circulation and contact of the tanning-liquid is obtained about and upon such leather, and the tanning process is more readily, effectually, and uniformly carried out, for it is clear that if a portion of one side of leather lies against another, as is always the case, due to the unevenness or irregularity in the surfaces of the sides, such contact and consequent prevention of the circulation of the tanning-liquid is obviated by the described vibration of the leather.

Having thus described my invention, what I claim, and desire to secure by Letters Patent, 85 is—

1. The combination, with a suitable actuating mechanism, of a pair of journaled bars provided with a series of hooks or leather-supports above its center of vibration, and a similar series below its center of vibration, all arranged in relation to a tanning-vat and for operation substantially as described, for the 90 purpose specified.

2. The combination, with a suitable actuating mechanism, of a pair of journaled bars provided with a series of hooks or leather-supports above its center of vibration, and a similar series below its center of vibration, each hook of which lower series is in a different 100 transverse plane in relation to its carrying-bar from the hooks of the upper series, all arranged in relation to a tanning-vat and for operation substantially as described, for the purpose specified.

3. The combination, with a centrally-journaled bar or bars provided with two series of hooks, one upon each side of the center of such bar, and the hooks of each series alternately arranged in relation to those of the 110 other series of each bar, of a connecting-rod between the said bar or bars and the driving-shaft, that is adapted to be attached and detached at will, substantially as described, for the purpose specified.

4. In combination with a suitable driving means, a pair of journaled bars, C D, having hooks E, and each provided with rigid arms F, connected by rod K, and a connecting-rod, G, between its arm F and the driving means, 115 which connecting-rod is adapted to be removed from its operative connection, substantially as described.

In testimony that I claim the foregoing as my invention I have signed my name, in the 120 presence of two witnesses, this 25th day of October, 1886.

RUDOLPH J. MEISER.
